UNITED STATES PATENT OFFICE

WILLIAM C. DEVEREAUX, OF DETROIT, MICHIGAN, ASSIGNOR TO FERRO STAMPING & MANUFACTURING COMPANY, OF DETROIT, MICHIGAN, A CORPORATION OF MICHIGAN

DOOR LATCH

Application filed November 23, 1925. Serial No. 70,906.

This invention relates generally to door latches particularly designed for use upon the doors of vehicle bodies and consists of certain novel features of construction, combinations and arrangements of parts as will be more fully described and particularly pointed out in the appended claims.

In the accompanying drawings:

Figure 1 is a fragmentary elevation of a door with a latch mechanism embodying my invention applied thereto.

Figure 2 is a fragmentary elevation of the latch mechanism.

Figure 3 is a fragmentary elevation of the remote operating means.

Figure 4 is a view similar to Figure 3 but showing the rollback in dogging position.

Referring now to the drawings, the numeral 1 designates a latch case plate that is secured to the inner side of a door and is provided at its forward edge with a laterally extending flange 2 that is secured to the outer edge of the door. Slidably mounted on the case plate 1 and movable through a suitable opening in the flange 2 is a latch bolt 3 having a rearwardly projecting cylindrical extension 4 slidably engaging a suitable guide lug 5 on the case plate 1. Any suitable means such as the coil spring 6 sleeved on the extension 4 between the lug 5 and bolt 3 may be employed for normally holding the bolt in projected position.

For retracting the bolt 3 against the tension of the spring 6, I preferably provide two distantly spaced rollbacks 7 and 8 respectively. As shown, the rollback 7 is journaled in the case plate 1 adjacent to the flange 2 and is adapted to be operated from the outside of the door at a point adjacent to the outer edge thereof, while the rollback 8 is swingingly mounted on a separate case plate 9 on the inner side of the door and is adapted to be operated from the inside of the door preferably at a point substantially midway between the side edges thereof. In order that the bolt 3 may be easily and quickly retracted by the rollback 7, I preferably provide a plate 10 that has a lateral flange 11 adapted to be engaged by the rollback 7 and that has spaced laterally projecting lugs 12 engageable with

a pin 13 which extends transversely through the extension 4 at the rear end thereof. As shown, this plate 10 is slidably mounted on the case plate 1 and is provided with lateral tongues 14 that are adapted to travel in suitable elongated guide slots 15 in the case plate 1. Any suitable means such as the helical spring 16 anchored on the case plate 1 may be employed for normally holding the plate 10 in its forward position so that the flange 11 will be in operative position with respect to the rollback 7.

In order that the bolt 3 may be readily retracted at a remote point, I preferably provide a bar 17 that is slotted to receive the arm 18 of the rollback 8 and that is connected to the slideable plate 10 by means of a rod or link 19. As shown, the slot 20 in the bar 17 is elongated to permit the bar to be moved rearwardly by the rollback 7 without disturbing the rollback 8 and to permit the latter to be swung forwardly as will be hereinafter described. Thus, when the rollback 7 is swung rearwardly against the lateral flange 11, the lugs 12 of the plate 10 will engage the pin 13 in the extension 4 and will cause the bolt 3 to be retracted; likewise when the rollback 8 is swung rearwardly against the rear wall 21 of the slot 20, the bar 17, link 19 and plate 10 will move as a unit and will cause the lugs 12 of the latter to engage the pin 13 to retract the bolt without disturbing the rollback 7. Hence the rollbacks 7 and 8 respectively may be independently operated. Moreover the connection between the bolt 3 and plate 10 is such that the bolt is free to move inwardly when the door is closed without disturbing either rollback.

In devices of this kind it is desirable to provide some means for rendering inoperative the bolt retracting member that is actuated from the outside of the door. In the present instance this is accomplished by providing the rollback 8 with an arcuate edge portion 22 that may be moved into snug engagement with a correspondingly shaped recess 23 in the upper edge of the bar 17. Inasmuch as the bar 17, link 19 and plate 10 move as a unit, it will be apparent that the engagement of the arcuate edge portion 22

100

with the recess 23 will automatically cause the flange 11 on the plate 10 to hold the rollback 7 against rearward bolt retracting movement. Hence, the rollback 7 may be rendered inoperative from a remote point. Moreover the rollback 8 may be moved in one direction to retract the bolt and may be moved in opposite direction to render the rollback 7 inoperative, thus, serves a double function. In order that the rollback 8 may be detachably held in position to retract the bolt or in position to render the rollback 7 inoperative, I preferably provide a leaf spring 24 that is secured at its opposite ends to a marginal flange 25 of the case plate 9 and that is provided intermediate its ends with a substantially V-shaped finger portion 26 that is adapted to automatically engage the spaced notches or recesses 27 and 28 respectively in the upper edge of the rollback 8.

Thus, from the foregoing description, it will be readily apparent that the present construction eliminates the necessity of passing the latch lever through the garnish rail or molding of the door. Inasmuch as the operating handle (not shown) for the inside rollback 8 is positioned upon the inner side of the door, it will also be apparent that it is very accessible and may be easily and quickly operated for actuating the bolt. Due to its location, the inside operating handle may also be readily used from the inside of the vehicle to pull the door from open to closed position.

While it is believed that from the foregoing description, the nature and advantage of my invention will be readily apparent, I desire to have it understood that I do not limit myself to what is herein shown and described and that such changes may be resorted to when desired as fall within the scope of what is claimed.

What I claim as my invention is:

1. The combination with a latch bolt and a member for operating the same adjacent thereto, of a swingingly mounted bolt retracting member located at a remote point from said bolt, and means adapted to be actuated by one part of the second mentioned member for retracting the bolt and adapted to be engaged by another part of said member to render the first mentioned bolt operating member inoperative.

2. The combination with a latch bolt and means for actuating the same adjacent thereto, of a bolt retracting member remotely positioned with respect to said bolt, and a connection between the latch bolt and said bolt retracting member adapted to be actuated by one portion of said member for actuating the bolt and adapted to be engaged by another portion of said member for rendering the first mentioned bolt actuating means inoperative.

3. The combination with a latch bolt and

means for actuating the same adjacent thereto, of a bolt retracting member located at a remote point from the bolt, and an operating connection between the retracting member and bolt movable in one direction by said member to retract the bolt and adapted to be held immovable by said member to render the first mentioned bolt actuating means inoperative.

4. The combination with a latch bolt and means for actuating the same adjacent thereto, of a bolt retracting member remote from the bolt movable in one direction to actuate the bolt and movable in another direction to hold the bolt immovable whereby the first mentioned bolt actuating means will be rendered inoperative and yieldable means for automatically holding said bolt retracting member in position to retract the bolt and in position to render the first mentioned means inoperative.

5. In a latch, the combination with a latch bolt and means for actuating the same adjacent thereto, a bar connected to said bolt having a recess therein and a rollback located at a remote point from said bolt having a portion engageable with said bar for actuating the bolt, and having another portion movable into the recess for holding the bolt against movement whereby the first mentioned actuating means will be rendered inoperative.

6. In a latch, the combination with a latch bolt and means for actuating the same adjacent thereto, a bar connected to said bolt having a slot and a recess therein, and a rollback having an arm engageable with one wall of the slot for actuating the bolt, and having an arcuate edge portion movable into the recess for holding the bolt against movement whereby the first mentioned bolt actuating means will be rendered inoperative.

7. In a latch, the combination with a latch bolt having a rearward extension, of a rollback located a substantial distance from the bolt having an arcuate portion engageable in a corresponding recess in said extension for holding the bolt against movement.

8. In a latch, the combination with a latch bolt, of means for actuating said bolt from a remote point including a member connected to said bolt and extending rearwardly therefrom a rollback having an arm engageable in a slot provided in said member, and yieldable means for detachably holding said rollback in position to retract the bolt.

9. In a latch, the combination with a latch bolt, of means for actuating the bolt from a remote point including a rollback operable in one direction to retract the bolt and operable in another direction to hold the bolt against movement.

10. In a latch, the combination with a latch bolt, of a rearward extension therefor having a slot and a recess therein, and a bolt retracting member remotely located with re-

spect to said bolt having projections respectively engageable with a wall of said slot and a wall of said recess for alternately actuating said bolt and holding the said bolt against movement.

11. In a latch, the combination with a latch bolt, of a rearward extension therefor having a slot and an arcuate recess therein, and a rotatably mounted bolt retracting member remotely located with respect to said bolt having radial projections respectively engageable with a wall of said slot and a wall of said recess for alternately actuating said bolt and holding the said bolt against movement.

12. In a latch, the combination with a latch bolt, of a reciprocating rearward extension therefor having two recesses therein, and a bolt retracting member remotely located with respect to said bolt having two projections respectively engageable with walls of the recess aforesaid for alternately actuating said bolt and holding the said bolt against movement, said bolt retracting member having two recesses therein, and means for alternately holding the projections aforesaid in their respective operative positions including a yieldable element alternately engageable with the recess in said bolt retracting member.

13. In a latch, the combination with a latch bolt, of actuating means therefor including a reciprocating member operatively associated with said bolt and constituting a rearward extension therefor, and a bolt retracting member remotely located with respect to said bolt and having a portion adapted to engage a portion of said reciprocating member, and yieldable means engageable with said bolt retracting member for yieldably maintaining a portion aforesaid of said bolt retracting member in operative relation with respect to said reciprocating member.

14. In a latch, the combination with a latch bolt, of actuating means therefor including a reciprocating member operatively associated with said bolt and constituting a rearward extension therefor, and a rotatable bolt retracting member remotely located with respect to said bolt and having a portion engageable with the reciprocating member for holding the said member against movement.

15. In a latch, the combination with a case plate and a latch bolt carried thereby, of a bar operatively connected to the bolt and constituting a rearward extension therefor, of means engageable with a portion of said bar for retracting said bolt, and means associated with the means aforesaid engageable with another portion of said bar for preventing retraction of said bolt by the first mentioned means.

16. In a latch, the combination with a case plate and a latch bolt carried thereby, of a reciprocating bar operatively connected to the bolt and constituting a rearward exten-

sion therefor, said bar having a slot and a recess therein, means engageable with a wall of said slot for retracting said bolt, and means associated with the means aforesaid and engageable with a wall of said recess for preventing retraction of the bolt by the means aforesaid.

17. In a door latch, a latch bolt, remote control mechanism including slidable means constituting a rearward extension of said bolt, a member distant to the bolt for sliding said means to effect a retraction of the bolt, means carried by the member for restraining the slidable means from sliding, and a second member operatively associated with said slid- 75 able means whereby it may effect a retraction of the bolt when the slidable means is free to slide and is rendered inoperative for re- tracting the bolt when the slidable means is restrained as aforesaid.

18. In a door latch, a latch bolt, remote control mechanism including a slidable bar projecting rearwardly from the bolt and operatively connected thereto, a pivotally mounted member at the rear end of said bar for sliding the bar to effect a retraction of the bolt, means carried by said member for restraining the bar from sliding, and a second member operatively associated with said bar whereby it may effect a retraction of 90 the bolt when the bar is free to slide and is rendered inoperative for retracting the bolt when the bar is restrained as aforesaid.

19. In a door latch, a latch bolt, and re- 100 mote control mechanism associated with said latch bolt and including a reciprocable bar operatively connected to said bolt and constituting a rearward extension thereof, a member engageable with said bar at the rear end thereof to effect a retraction of the bolt, and means carried and operable by said member for holding the bar against movement.

20. In a door latch, a case plate attachable to a door at an upright edge thereof, a sec- 110 ond case plate remote to the first and attachable to the door intermediate its upright edges, a rollback on the first plate, a rollback on the second plate, a connection between said rollbacks including an element movable to retract the bolt, and means associated with the second plate for restraining the element against movement whereby the rollback on the first plate will be rendered inoperative.

21. In a door latch, a case plate attachable to a door at an upright edge thereof, a latch bolt carried by said case plate, a rollback carried by the case plate, a second case plate remote to the first and attachable to the door intermediate its upright edges, a rollback carried by the second plate, slid- 120 able means extending from the second rollback to the bolt and first rollback respectively and operable by either rollback to effect a retraction of the bolt, and means associated with the second rollback for rendering the slid- 125 able means 130

means immovable so that the first rollback cannot be operated to effect a retraction of the bolt.

22. In a door latch, a case plate attachable to a door at an upright edge thereof, a latch bolt carried by said case plate, a second case plate remote to the first and attachable to a door intermediate its upright edges, slidable means extending from the second plate and operatively connected to the bolt, means on the second plate for actuating the slidable means to effect a retraction of the bolt, means associated with the last mentioned means for holding the slidable means against movement, and means on the first case plate operable when the slidable means is free to effect a retraction of the bolt and rendered inoperative by the slidable means aforesaid when it is held against movement.
23. In a door latch, a latch bolt, a member for retracting said bolt, and remote control mechanism associated with the bolt including a slidable bar associated with the bolt retracting member aforesaid and operable to retract the bolt, an operating member for the bar movable in one direction to effect a retraction of the bolt, and means rendered effective when the operating member is moved in another direction to dog the bar and cause the bolt retracting member aforesaid to be rendered inoperative.
24. In a door latch, a latch bolt, means for retracting the bolt, including remote control mechanism having slidable means constituting a rearward extension of the bolt, and actuating means for the slidable means including means at the rear end of said slidable means for holding the said slidable means against sliding.
25. In a door latch, a latch bolt, means for retracting the bolt, including remote control mechanism having slidable means constituting a rearward extension of the bolt, and a movable element having means for sliding the slidable means and having other means for holding the slidable means against sliding.
26. In a door latch, a latch bolt, and remote control mechanism associated with the bolt and including an element movable in two directions, slidable means constituting a rearward extension of the bolt, operable by said element when it is moved in one direction to effect a retraction of the bolt, and rendered inoperative by said element when moved in the other direction.
27. In a door latch, a latch bolt, and remote control mechanism associated with the bolt including a pivotally mounted element, slidable means constituting a rearward extension of the bolt operable by said element when it moves in one direction about its pivot to effect a retraction of the bolt, and rendered inoperative by said element when it moves in the opposite direction about its pivot, and

an element movable when the slidable means is moved to effect a retraction of the bolt and held by said slidable means against movement when said means is inoperative.

28. In a door latch, a latch bolt, an operating member, and remote control mechanism including slidable means constituting a rearward extension of the bolt and operable by the operating member to effect a retraction of the bolt, and means at the rear end of the slidable means for alternately actuating said means and holding the same against operation by the member aforesaid.

29. In a door latch, a latch bolt, remote control mechanism including slidable means constituting a rearward extension of said bolt, pivotally mounted means distant to the bolt for sliding said means to effect a retraction of the bolt, means operable by the pivotally mounted means for restraining the slidable means from sliding, and a second member operatively associated with said slidable means whereby it may effect a retraction of the bolt when the slidable means is free to slide and is rendered inoperative for retracting the bolt when the slidable means is restrained as aforesaid.

In testimony whereof I affix my signature.

WILLIAM C. DEVEREAUX.
